[57] **CLAIM**

The ornamental design for a contact housing for an electrical connector, as shown and described.

DESCRIPTION

FIG. 1 is a top frontal view in perspective of a contact housing for an electrical connector embodying my new design, shown in use with a complimentary connector and wires shown in phantom lines;

FIG. 2 is a top frontal view in perspective of a contact housing for an electrical connector embodying my new design;

FIG. 3 is a bottom frontal view in perspective thereof;

FIG. 4 is a front elevational view thereof;

FIG. 5 is a left side elevational view thereof, and the right side is a mirror image thereof;

FIG. 6 is a rear elevational view thereof;

FIG. 7 is a top plan view thereof; and,

FIG. 8 is a bottom plan view thereof.

The phantom lines in FIG. 1 illustrate environmental structure only which forms no part of the claimed design.
